(57) **CLAIM**

The ornamental design for a climbing aid, as shown and described.

DESCRIPTION

FIG. 1 is a perspective view of a climbing aid according to my new ornamental design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines represent environmental structure or unclaimed portions of the climbing aid and do not form a portion of the claimed design.
